Primary Examiner — John Windmuller*Assistant Examiner* — Melvin L Davis(74) *Attorney, Agent, or Firm* — Traverse Legal, PLC(57) **CLAIM**

I claim the ornamental design for a modular display fixture, as shown and described.

DESCRIPTION

FIG. 1 is a perspective view of a modular display fixture in a usage condition;

FIG. 2 is a perspective view of the modular display fixture in an alternate usage condition;

FIG. 3 is a perspective view thereof;

FIG. 4 is a front view thereof;

FIG. 5 is a back side view thereof;

FIG. 6 is a left side view thereof;

FIG. 7 is a right view thereof;

FIG. 8 is a top view thereof; and,

FIG. 9 is a bottom view thereof.

The broken lines in the drawings are included for purposes of illustrating environment and form no part of the claimed design.
